UNITED STATES PATENT OFFICE.

JOHN C. SANGERS, OF CLEVELAND, OHIO.

CURTAIN STRETCHER.

Application filed June 24, 1922. Serial No. 570,674.

To all whom it may concern:

Be it known that I, JOHN C. SANGERS, a citizen of the United States, residing at Cleveland, in the county of Cuyahoga and State of Ohio, have invented a certain new and useful Improvement in Curtain Stretchers, of which the following is a full, clear, and exact description, reference being had to the accompanying drawings.

This invention relates to an improved curtain stretcher, and its objects are to provide a device of this character wherein all the pin carrying members of the curtain supporting frame are in a common plane, thereby avoiding the objectionable offsets which are present in those types of curtain stretchers having certain of the frame members overlapping; to provide a device of the foregoing character which is particularly convenient of use in that it may be lowered to a position wherein all parts of the frame are in easy reach of the user and, after the curtain or curtains is or are applied thereto, may be stood substantially upright so as to occupy little floor space, making it possible to stand it alongside a stove or other heating apparatus where it is least in the way and so that the heat will be applied to the curtain or curtains to the best advantage; to provide a curtain stretcher wherein certain of the frame members are so connected as to insure a right-angular relation between them, and to graduate the frame members into inches or other standards of measurement so that the remaining frame members may be readily set in like relation and adjusted to curtains of various sizes; to provide a curtain stretcher having a very wide range of adjustment so that curtains from the largest to the smallest practical sizes may be accommodated thereon; to provide a curtain stretcher that may be very readily assembled and as easily disassembled and which is foldable into a comparatively small space; to provide clamping means for connecting certain of the frame members together which enables one member to be connected at any point longitudinally of another member without having to engage it over the end of said member and move it therealong to the desired position; to form the frame members so as to cause an interlocking between them which will enhance the character of the connection; and to provide a unique form of clamp for securing the

struts or stays to the frame members and for frictionally holding said parts in any adjusted position.

The foregoing objects, and others which will hereinafter appear are obtained in the embodiment of my invention illustrated in the accompanying drawings which constitute a part hereof and wherein Fig. 1 is a perspective view of my improved curtain stretcher; Fig. 2 is a fragmentary front elevation of the frame; Fig. 3 shows, in rear elevation, the parts of Fig. 2; Fig. 4 shows the same parts in folded condition as though viewed from the rear side; Fig. 5 is a section on the line 5—5 of Fig. 2; Fig. 6 is a section on the line 6—6 of Fig. 3; Fig. 7 shows in perspective the upper end of one of the struts or braces, and the clamp for securing it to one of the upright members of the frame; and Fig. 8 is a horizontal section through one of the upright members immediately above the clamp.

The frame is made up of side members 1 and 2, a top member 3, and a bottom member 4. The side member 1 is composed of upper and lower sections 1^a and 1^b, respectively, which are hingedly connected together by a hinge strap 5 that is pivoted at 6 and 7 to the respective sections 1^a and 1^b (Figs. 3 and 4). A channel 8, having one of its ends engaged over and connected as by screws 9 to the lower outer edge portion of the section 1^a, is adapted to embrace the adjoining outer edge portion of the section 1^b, when said sections are in alignment, for the purpose of effecting a rigid joint between them, and said sections may be locked in this condition by a thumb nut 10 that is screwed onto a stud 11 which is carried by the section 1^b and projects through a hole in the web of the channel 8.

A hinge strap 15, which is pivotally connected at 16 to the rear side of the upper end of section 1^a, and which is rigidly secured by fastening means 17 to the adjacent end of the top member 3, hingedly connects the frame members 1 and 3 so that they may be swung from one to the other of their extreme positions. In one of such positions, as shown in Figs. 2 and 3, the members occupy a right-angular relation, the parts being held in this condition by a spring latch 18, carried by the member 3, which engages a pin 19, in the upper end of the member 1. When it is desired to fold members 1 and 3 into compact form, the latch 18 is disen-

gaged from pin 19 and member 3 is swung down alongside section 1^a, and section 1^b is released from the channel 8 through the manipulation of the thumb nut 10 and is folded up along the side of member 3 opposite that occupied by section 1^a, as clearly shown in Fig. 4. The free end of the section 1^b, is retained in the plane of member 3 by being engaged over the protruding end portion 20 of the hinge strap 15.

Sections 2^a and 2^b, of the frame member 2, are hingedly connected in a manner similar to that in which the sections of member 1 are connected, the hinge strap which connects sections 2^a and 2^b, however, being shorter than the hinge strap 5 of the former member, the extra length in this case being unnecessary, inasmuch as the two sections 2^a and 2^b lie directly together when folded. 29 This is such a slight and obvious difference, that illustration of the latter connection is deemed unnecessary. The sections are held in alignment by a channel 25 when a stud 26, that is carried by the section 2^b, is engaged through an aperture of the channel and has applied to it a wing nut 27. The upper end of the member 2 is adapted to be adjustably secured to the top member 3 by means of a clamp 30 which is identical with 30 a clamp which I shall presently describe in connection with the frame member 4.

The member 4 is comprised of sections 4^a and 4^b which are held in edgewise engagement and in the same plane by a plate 33 that is secured, by fastening means 34, to the rear side of section 4^b and overlies the adjacent edge portion of the rear side of section 4^a, the plate being provided with a longitudinal slot 35 through which a threaded stud 36 projects from the section 4^a. To assist in holding the sections 4^a and 4^b in parallel relation, a member 37, which is carried by the section 4^a, also extends through the slot 35 and is provided therebeyond with 45 a head. This construction enables the member 4 to be lengthened and shortened; and the sections thereof are adapted to be secured in any adjusted position by a wing nut 30 that is screwed onto the stud 36. The 50 adjacent edges of sections 4^a and 4^b have applied to them metallic straps 40 to which are secured pins 41, the straps being relatively thin and preferably of rust-proof metal. This arrangement brings the pins of the sections 4^a and 4^b nearly enough into alignment for all practical purposes.

The inner edges of the sections 1^b and 2^b of the respective side members 1 and 2 are beveled slightly, the surfaces of said edges 60 converging rearwardly; and the ends of member 4 are reversely beveled so as to slightly overhang the beveled edges of said sections. Secured to the rear side of each end of the member 4 is the shank of an L-shaped clamp 45. A thumb screw 46 is

threaded through the laterally disposed end of each clamp and, when turned up, is adapted to engage the respective side member of the frame and force it into firm engagement with the adjacent end of the member 4. 70

The previously mentioned clamp 30 of the side member 2 may be identical with the clamps 45; and the upper end of the member 2 and the edge portion of member 3 wherewith it engages are beveled and interfit like 75 the corresponding parts of the member 4 and sections 1^b and 2^b, above described.

Struts or stays 50 are adjustably connected to the side members 1 and 2 by a clamp illustrated in detail in Figs. 7 and 8. The 80 clamp of each strut or stay is composed of substantially identical side plates 51 that are applied, in opposed relation to each other, to the opposite edges of the upper end of the corresponding strut or stay 50, and a bolt 52 passes through a transverse bore of the strut and through apertures in the aforesaid plates which register with said bore. The head 53 of the bolt engages one of the side plates, and a wing nut 54, which is 85 screwed on the threaded end of the bolt, engages the other side plate. The forward edges of the plates 51 are provided with inwardly directed flanges 55 for engagement within longitudinal grooves in the opposite edges of the frame member wherewith the clamp is adapted to be connected. The lower rear edge portions of the plates 51 are turned inwardly to provide stops 56 for engagement with the strut or stay to limit in one direction its angular movement with respect to the frame member. The plates 51 may be strengthened by being flanged at 57 along their lower edges. When the thumb nut 54 is loosened, the clamp may be slid to any desired position along the upper section of the side member, and the strut 50 swung to a proper angular position; and when the parts are placed in the desired relation, they may be secured therein by tightening the thumb 105 nut 54. Even when the thumb nut is comparatively tight, the strut or stay 50 may be angularly adjusted with respect to the frame member, and it is frictionally retained by the clamping plates in such adjusted position. 110

I have already explained how the frame member 4 is equipped with the curtain holding pins 41. The side members 1 and 2 and top member 3 carry pins 58. All of the pin carrying members of the frame are graduated into inches or other units so as to facilitate setting the stretcher for any size curtain. 120

It will be seen from the foregoing that my invention provides a curtain stretcher which is very convenient of use, being readily adjustable to curtains of various sizes and being so constructed as to insure the frame members being in right angular relation to 130

each other when set up for use, and having its parts so connected as to facilitate assembly, disassembly and folding. Attention is also directed to the fact that there are no fittings which objectionably extend over the front surface of the frame to interfere with the attachment of the curtains to the pins.

Having thus described my invention, what I claim is:

1. In a curtain stretcher, the combination of a frame member having longitudinal grooves along its opposite edges, a strut of substantially the same width as said member, clamping plates applied to the opposite edges of one end of said strut and having inwardly turned flanges for engagement within the grooves of the frame member, means passing through and connecting the plates and strut and by means of which said plates may be drawn together into frictional engagement with the frame member and strut, said plates having stop portions for restraining the strut against undue angular movement with respect to the frame member.

2. In a curtain stretcher, the combination of a pair of longitudinal frame members comprising hinged sections, adapted to be folded one upon the other, lateral frame members adapted to be adjustably connected with said longitudinal frame members, one of said lateral frame members comprising two relatively movable sections and a pin and slot connection between said relatively movable sections, means for adjusting the relative position of said two sections, one end of each section being beveled and having a clamping plate secured thereto having an overturned flange and thumb screws threaded therethrough for clamping said sections to said longitudinal frame members, and a complementary bevel on said longitudinal

frame members, whereby said sections may be rigidly secured in place.

3. In a curtain stretcher, the combination with a pair of frame members, said frame members being composed of hinged sections, the upper section having grooves in its opposite edges adapted to receive clamping plates, said clamping plates having struts pivotally connected thereto, sectional frame members adjustably connected with said first named frame members, one of said sectional frame members having its ends beveled and clamping plates carried thereby, said last mentioned clamping plates having overturned flanges and thumb screws threaded therethrough, whereby said sectional frame member may be adjustably clamped to said first named frame members.

4. In a curtain stretcher, the combination with a pair of frame members, said frame members being composed of hinged sections, the upper section having grooves in its opposite edges adapted to receive clamping plates, said clamping plates having struts pivotally connected thereto, sectional frame members adjustably connected with said first named frame members, one of said sectional frame members having its ends beveled and clamping plates carried thereby, said last mentioned clamping plates having overturned flanges and thumb screws threaded therethrough, whereby said sectional frame member may be adjustably clamped to said first named frame members, one of said sectional frame members being composed of two relatively movable sections and a pin and slot connection between said two sections, and clamping means for adjusting the relative position of said two sections.

In testimony whereof, I hereunto affix my signature.

JOHN C. SANGERS.
